LIGHT-RAY BAFFLE

Charles U. Deaton, Denver, Colo.

Application July 20, 1956, Serial No. 42,325

Term of patent 14 years

(Cl. D48—16)

FIG-1

FIG-2

FIG-3

Figure 1 is a perspective view of a light-ray baffle embodying my new design;

Figure 2 is a bottom plan view thereof; and

Figure 3 is a side elevational view thereof.

The dominant features of the design reside in the portions shown in full lines.

I claim:

The ornamental design for a light-ray baffle, substantially as shown and described.
